UNITED STATES PATENT OFFICE.

MATTHIAS BROCK, OF BOSTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

PROCESS OF MAKING SHOES.

1,273,323.

Specification of Letters Patent. Patented July 23, 1918.

Original application filed June 10, 1914, Serial No. 844,209. Divided and this application filed June 14, 1916. Serial No. 103,647.

To all whom it may concern:

Be it known that I, MATTHIAS BROCK, a citizen of the United States, residing at Boston, in the county of Suffolk and State 5 of Massachusetts, have invented certain Improvements in Processes of Making Shoes, of which the following description, in connection with the accompanying drawings, is a specification, like reference characters 10 on the drawings indicating like parts in the several figures.

This invention relates to processes of making boots and shoes. A general object of the invention is to provide an improved 15 process of treating shoes, preferably as an intermediate step in their manufacture, which will permanently increase their size. In the following description particular reference is made to its utility in a new process 20 of making stitch-down shoes. A machine which may be used for carrying out this process forms the subject-matter of a co-pending application Serial No. 844,209, filed June 10, 1914, of which this application is 25 a division. It will be understood, however, that the invention is not restricted to employment in making shoes of this particular kind but is of utility generally in the manufacture of shoes, whether the shoes be made 30 by the stitch-down process, turn shoe process, or any of the well-known processes of making shoes.

In the manufacture of shoes by the former process disclosed in United States Letters 35 Patent No. 931,851, granted August 24, 1909, on application of Karl Engel, the toe and heel ends of the shoe upper are molded to the shapes of the corresponding parts of a last and an innersole is stitched to said upper before said upper is placed upon the last. To insure the production of a properly fitting shoe by this process it is substantially essential that the upper should be cut very carefully to pattern and that the insole 40 45 should be stitched carefully to the molded upper. When this is done difficulty is experienced in inserting the last particularly in the manufacture of the large sizes of shoes; and moreover the mere insertion of a

last of the proper size in a shoe thus made 50 does not effect such proper stretching of the upper in all directions as is essential to the production of a finished shoe having a neat and smooth appearance. An important object of the present invention, therefore, is to 55 provide a new process of making shoes adapted without sacrifice of their utility to be employed to advantage in the manufacture of shoes made in accordance with the general principles of operation of the process 60 disclosed in the Letters Patent above-identified, said new process comprising as a further important step a stretching of the upper preferably in various directions along different dimensions whereby those parts of 65 the upper which are not shaped by the toe and heel molding operations may be properly stretched as an intermediate step between the molding and insole securing operations on the one hand and the insertion of 70 the last upon which the shoe is supported for the finishing operations on the other hand.

An important feature of the present invention consists in treatment of the shoe 75 upper materials after the upper has been shaped and secured to the sole so as permanently to increase the size of the shoe, whereby a material saving in stock may be effected. Preferably by this process the 80 stretching is effected by relative movement of the members which are placed within the shoe and conform more or less exactly to the shape of the finished shoe, the members comprising a forepart member and a rear 85 part member which may be moved relatively longitudinally of the shoe to stretch the shoe in the direction of its length. The member which engages the forepart of the shoe may be divided longitudinally of the shoe and 90 the parts given relative movement to stretch the forepart of the shoe in the direction of its width.

Preferably the amount of stretching to which the forepart is subjected increases 95 progressively from the toe toward the ball of the forepart, there being little or no lateral stretching effected at the toe of the shoe

which has already been molded to the required form for the last. To secure uniformity of product, it is important that the stretching members be first moved longitudinally and laterally of the shoe to correspond substantially to the size of the shoe which has been placed upon them and they may be thus set to a predetermined size which does not materially stretch the shoe.

10 The members may then be moved laterally and longitudinally of the shoe predetermined distances which are preferably sufficient to increase the size of the stretching means to correspond to the next larger size

15 ~~of~~ shoe whereby the shoe is stretched to a predetermined larger size.

As another important step in the process, the heel seat is shaped by forming pressure applied to the heel seat against the stretching member which fills the rear part of the shoe, and preferably the heel seat forming step is performed prior to, or simultaneously with, the stretching operation.

Preferably the shoe is now allowed to remain under stretching tension for a time sufficient to allow the parts to become substantially set in their stretched condition. The stretching means is then contracted and the shoe removed therefrom and placed upon a last corresponding to the size to which the shoe has been stretched. Then if the shoe is to have a second sole, this is laid upon the shoe in the usual manner to form the outsole of the shoe and is stitched to the outwardly projecting flange of the upper and innersole, a welt strip being preferably applied to the upper face of the projecting flange and sewed to the upper and innersole by the stitches which attach the outsole to the shoe.

Figure 1 represents a shoe upper with the toe part and heel part molded with out-turned flanges as a preliminary step in my improved process;

45 Fig. 2 represents the application of the upper molded as in Fig. 1 to an innersole cut to the size required by the given upper;

Fig. 3 represents the upper attached to the innersole by a line of stitches and ready 50 for the stretching operation;

Fig. 4 is a sectional view of the shoe shown in Fig. 3 placed upon the stretching means, the stretching means being set so as substantially to fill the shoe and the heel seat forming means being in operative position.

Fig. 5 is a sectional view of the shoe shown in Fig. 4 after the shoe has been stretched and the heel seat formed;

Fig. 6 is a perspective view showing an exemplary means for effecting the lateral stretching of the forepart; and

Fig. 7 is a perspective view of the shoe after the stretching operation and prior to the attachment of the outsole.

In the practice of this improved process, 65 the heel and toe portions of the upper are molded substantially to the shape required in the finished shoe, and, in the case of a stitch-down shoe, have the marginal edge of the upper turned outwardly to form a 70 sole attaching flange as is clearly shown in Fig. 1 of the drawings. These preliminary toe and heel molding operations may be performed in any suitable manner or in accordance with the molding methods disclosed in United States Letters Patent No. 947,895, granted February 1, 1910, and No. 1,001,745, granted August 29, 1911, on applications of Karl Engel.

The upper thus molded is next assembled 80 as indicated in Fig. 2 upon an innersole of the proper shape which is preferably substantially that of the sole of the finished shoe. This innersole, which may be of comparatively light stock, is then secured to the 85 upper wholly or partially around the periphery of the shoe and is, for example, shown as secured by stitches which pass through the outturned margin or flange of the upper and the margin of the innersole 90. The shoe has now reached the stage in its manufacture represented in Fig. 3 and is preferably of a given size which for purpose of illustration will be called size 7. At this stage in its manufacture the shoe is subjected to the stretching operation which may be effected by placing the shoe upon a last-like form having relatively movable heel and forepart sections, for example, the parts 10 and 12 as shown in Fig. 4. After the shoe 100 has been placed upon the form, the form is set in the present instance to the size corresponding to that of the shoe, the form then, of course, substantially filling the shoe. The parts 10, 12 are then moved relatively to 105 stretch the shoe longitudinally and preferably are moved a predetermined distance to increase the size of the shoe a given amount, in this instance to size 8. The relative movement of the parts 10 and 12 may conveniently be effected by mechanism such as that shown in the application above referred to, for example, the forepart 12 of the stretching means may be moved relatively to the heel part by a connection 14 to one arm of 115 the bell-crank lever 26 mounted on a pivot 18 fixed relatively to the heel part 10 and having another arm connected by a rod 20 with operating mechanism for pulling on the rod to move the part 12 longitudinally of the 120 shoe.

The form of the shoe is preferably expanded laterally to effect stretching of the shoe in the direction of its width and this lateral stretching may conveniently be performed at the same time as the longitudinal stretching. A convenient construction for effecting this is shown in Fig. 6 where

the forepart of the stretching form is shown as divided longitudinally of the shoe into two parts 12, 16 which are pivoted together and to the longitudinally moving connecting member 14 near the end which enters the toe of the shoe and are provided with pins 22 which engage inclined slots 24 formed in relatively stationary parts. The pivoting of the parts 12, 16 together at the toe as described together with the lateral separation of these parts at their opposite ends which are located adjacent to the ball portion of the shoe by the action of the pins 22 in the slots 24 as the parts 12, 16 are moved longitudinally of the shoe, effects progressive lateral stretching of the forepart of the shoe which increases in extent progressively from the toe toward the ball and takes place simultaneously with the longitudinal stretching effected by movement of the members 12, 16 together longitudinally of the shoe and relatively to the stationary part 10.

The heel seat of the shoe may be shaped prior to, or simultaneously with, the stretching operation and convenient means for effecting this is shown in Figs. 4 and 5. This means comprises a U-shaped member 46 which is positioned longitudinally of the shoe by a stop 48 which engages the rear end of the shoe. Mechanism is preferably provided, as fully explained in the application above referred to, for forcing the member 46 firmly against the heel seat of the shoe during the stretching operation.

After the stretching operation has been performed as described, the shoe may be regarded as completed. To get the best results from my improved method, however, the sole first attached is of comparatively light stock susceptible of being stretched and is regarded as an innersole. Accordingly, to complete the shoe, a last of the size to which the shoe has been stretched is inserted in the shoe, an outersole is laid upon the shoe in the usual manner and is attached to the sole attaching flange of the shoe, this flange being formed, in the case of a stitch-down shoe, by the outturned upper and outwardly extending margin of the innersole. When the shoe is a stitch-down a welt strip is preferably applied to the exposed face of the outturned margin of the upper and is secured with the outersole to the sole attaching flange.

Having fully described my invention, I claim as new and desire to secure by Letters Patent of the United States:

1. That improvement in the art of making shoes which comprises molding to shape the heel and toe ends of a shoe upper off the last, attaching a sole to the upper, and then stretching the shoe permanently to increase its size.

2. That improvement in the art of making 65 shoes which comprises molding to shape the heel and toe ends of a shoe upper, attaching the sole to the upper and then stretching the shoe longitudinally permanently to increase its size.

3. That improvement in the art of making 70 shoes which comprises shaping the heel and toe ends of an upper substantially to the shape which they are to have in the finished shoe, attaching a sole to the upper, stretching the shoe as a whole longitudinally and stretching the forepart laterally permanently to increase the size of the shoe, and then completing the shoe.

4. That improvement in the art of making 80 shoes which comprises molding the toe part and the heel part of a shoe to substantially the form which they are to assume in the finished shoe, attaching the sole to the upper, and then stretching the forepart of the shoe 85 by progressively decreasing amounts from the ball portions toward the toe permanently to increase the size of the shoe.

5. That improvement in the art of making 90 shoes which comprises preparing the shoe upper off the last with a sole attached thereto, inserting a form in the shoe, adjusting the form to fill the shoe and then expanding the form, removing the form, inserting a last of substantially the size of the expanded 95 form, and then completing the shoe.

6. That improvement in the art of making 100 shoes which consists in preparing a shoe upper off the last with the sole attached thereto, inserting a form in the shoe, adjusting the form to fill the shoe, expanding the form a predetermined amount to stretch the shoe to a predetermined size, removing the form, inserting a last of a size to fit the stretched shoe, and then completing the 105 shoe.

7. That improvement in the art of making 110 shoes which consists in preparing a shoe upper off the last, attaching the sole thereto, inserting a form in the shoe, adjusting the form to fill the shoe, then expanding the form a predetermined amount longitudinally and expanding the forepart of the form laterally permanently to increase the size of the shoe.

8. That improvement in the art of making 115 shoes which consists in preparing a shoe upper off the last, attaching the sole thereto, inserting a form in the shoe, and expanding the form longitudinally and laterally permanently to increase the size of the shoe, the lateral expansion bearing a fixed ratio to the longitudinal expansion.

9. That improvement in the art of making 120 shoes which consists in molding the toe part of an upper to the desired shape of the toe of the finished shoe and simultaneously forming an outwardly projecting flange

- thereon, securing the margin of an inner-
sole to said flange, stretching the shoe per-
manently to increase its size, and securing an
outer sole to the margins of the upper and
5 innersole.
10. That improvement in the art of making
shoes which consists in molding the end
portions of the shoe to the desired shape of
the finished shoe and simultaneously form-
10 ing thereon outwardly projecting flanges,
securing the margin of the sole to the said
flanges, and then stretching the shoe to a
predetermined size.
11. That improvement in the art of making
15 shoes which consists in molding the toe part
of the upper to the shape of the toe of a
last and simultaneously forming an out-
wardly projecting flange thereon prior to
lasting, securing the margin of an innersole
20 to said flange, stretching the shoe to a given
size, inserting a last of the size to which the
shoe is stretched, and securing an outersole
to the margins of the upper and innersole.
12. That improvement in the art of making
25 shoes which consists in forming an out-
wardly turned flange on the toe part and
on the heel part of the upper, molding such
parts to the shape of the lasted shoe, turning
out the sides of the upper, and stitching
30 thereto and to the flanges an innersole,
stretching the upper longitudinally and
laterally from the ball portion toward the
toe permanently to increase the size of the
shoe, inserting a last in the stretched shoe,
35 and then completing the shoe.
13. That improvement in the art of making
shoes which consists in forming an out-
wardly turned flange on the toe part of an
upper, molding such part to the shape of a
40 lasted shoe, molding the counter and heel
stiffener of the upper to the shape of the
lasted shoe, and forming thereon an out-
turned flange, leaving the sides of the upper
unmolded, turning out the sides of the
45 upper, and attaching thereto and to said
flanges an innersole, stretching the shoe
laterally and longitudinally to a predeter-
mined extent permanently to increase the
size of the shoe, and securing an outersole
50 to the toe and counter flanges, to the inter-
mediate outturned sides of the upper and
to the margin of the innersole.
14. That improvement in the art of making
shoes which consists in molding the toe
55 and heel portions of a shoe upper and the
stiffeners therefor to the final shape of the
lasted shoe, forming thereon outturned
flanges, securing said flanges to the margin
of an innersole, stretching the shoe longitudi-
60 nally and laterally to a predetermined size,
inserting a last, and securing the outersole
to said flanges and to the outturned sides of
the upper.
15. That improvement in the art of mak-
ing shoes which comprises attaching an up-
per to a sole off the last, stretching the shoe
upper to increase its size, and inserting a
last in the attached upper and sole.
16. That improvement in the art of making
shoes which comprises attaching an up-
70 per to a sole off the last, stretching the shoe
thus formed to increase its size, inserting
a last of the size to fit the stretched shoe,
and then completing the shoe.
17. That improvement in the art of making
shoes which comprises attaching an up-
75 per to a sole off the last, stretching the shoe
thus formed to increase its length, inserting
a last of a size to fit the stretched shoe, and
then completing the shoe.
18. That improvement in the art of making
shoes which comprises attaching an up-
80 per to a sole off the last, stretching the shoe
thus formed to increase its width, inserting
a last of a size to fit the stretched shoe, and
then completing the shoe.
19. That improvement in the art of making
shoes which comprises molding portions
85 of a shoe upper, attaching a sole to the
molded upper while the upper is still off the
last, stretching the shoe thus formed perma-
nently to increase its size, inserting a last
in the stretched shoe, and then completing
the shoe.
20. That improvement in the art of making
shoes which consists in forming portions
90 of a shoe upper substantially to the shape
of a last and attaching the upper to a sole,
then stretching the shoe permanently to in-
crease its size, inserting a last of the size to
100 which the shoe has been stretched, and com-
pleting the shoe.
21. That improvement in the art of making
shoes which comprises preparing a shoe
upper with a sole attached thereto, stretch-
105 ing the shoe permanently to increase its size,
and then completing the shoe.
22. That improvement in the art of making
shoes which comprises attaching an up-
110 per to a sole off the last, stretching the up-
per permanently to increase its size, and
applying forming pressure to the heel seat.
23. That improvement in the art of making
shoes which comprises attaching an up-
115 per to a sole, stretching the upper perma-
nently to increase its size, applying forming
pressure about the marginal portion only
of the heel seat, inserting a last, and com-
pleting the shoe in the usual manner.
24. That improvement in the art of making
shoes which comprises attaching an up-
120 per to a sole, stretching the upper, applying
forming pressure about the marginal portion
of the heel seat simultaneously with the
stretching operation, inserting a last, and
125 completing the shoe in the usual manner.
25. That improvement in the art of making
shoes which comprises preparing a shoe

upper with a sole attached thereto, inserting a form in the shoe, adjusting the form to fit the shoe, holding the heel seat against movement away from the form, expanding the form to increase the size of the shoe, inserting a last of a size corresponding to the size of the stretched shoe, and then completing the shoe.

26. That improvement in the art of making shoes which consists in molding the heel part of an upper to the desired shape of the heel part of the finished shoe and simultaneously

neously forming thereon an outwardly extending flange, attaching an innersole to the margin of the upper including the said flange, applying pressure to the periphery of the heel seat of the shoe to cause the flange to be bent toward the top of the shoe upper, stretching the shoe simultaneously with the application of said pressure to the heel seat, and then completing the shoe.

In testimony whereof I have signed my name to this specification.

MATTHIAS BROCK.
